G. F. CHAMPNEY.
ART OF MAKING DIES.

2 Sheets—Sheet 2.

No. 499,820.

Patented June 20, 1893.

UNITED STATES PATENT OFFICE.

GEORGE F. CHAMPNEY, OF TAUNTON, MASSACHUSETTS, ASSIGNOR OF
THREE-FIFTHS TO ALFRED H. HARRISON, OF LONDON, ENGLAND.

ART OF MAKING DIES.

SPECIFICATION forming part of Letters Patent No. 499,820, dated June 20, 1893.

Application filed December 4, 1889. Serial No. 332,533. (No model.)

To all whom it may concern:

Be it known that I, GEORGE F. CHAMPNEY, a citizen of the United States, residing at Taunton, county of Bristol, and State of Massachusetts, have invented certain new and useful Improvements in the Art of Making Dies, fully described and represented in the following specification and the accompanying drawings, forming a part of the same.

10 My present invention relates to the making of steel dies. Hitherto these dies have been made by cutting directly from the solid block, and also by cutting from a solid steel block a patrice in relief, which is then pressed by slow degrees and repeated blows into the die block. Both methods are very tedious and costly and neither produces perfect work, since the traces of the tools are necessarily present. It has also been proposed to attach 15 the patrice to a drop hammer, place the block of steel while hot under it, and force the patrice into the block by dropping the hammer. The last mentioned process has had the advantage of much greater speed and economy 20 than those before mentioned, but is open to two considerable objections. The first of these is that where the work is delicate and difficult the die is likely to be imperfect. Thus, for instance, when figures portrayed 25 are sharp, particularly about the outer edge of its face, the angles are likely to be imperfectly reproduced in the die block and the distinctness of the original thus lost. As fine work abounds in parts thus difficult of reproduction this obstacle has been a serious one 30 to the value of the process. The second obstacle referred to is the liability of the patrice when made from cast iron or other fragile or soft metal, to be broken or crushed by the 35 force of the blow and thus fail to effect the desired impression.

My present invention is in the nature of an improvement upon the last mentioned process and is based upon the discovery that the 40 obstacles just stated can be avoided and the process perfected by giving to the patrice at the moment of its impact upon the die block an exceptionally high degree of speed. This 45 high velocity secures a result which, in the 50 perfection and certainty of the die produced, is new and which cannot be reached by merely

increasing the power of the blow by adding to the weight of the hammer. The new result is that all liability of the patrice, even when formed from cast iron, or from a comparatively soft metal, such as bronze, gold, silver or even copper, to be broken or crushed by contact with the die-block, is avoided, and also that the most delicate parts of the most difficult and finest work are brought out accurately in the die block and a perfect reproduction of the patrice secured, this being true even where the relief and intaglios of the patrice are very sharp and deep and finely drawn. The patrice passes so rapidly into 65 the steel of the die block that it does not receive enough of the force of the blow to injure it, the blow expending itself for the most part in the striking of the extended base of the patrice against the marginal top of the die 70 block; and the high velocity of the patrice not giving sufficient time for its breaking down away from the angles and sharp corners. Perfect dies are thus secured with great certainty and comparatively slight cost even for 75 the most complicated and delicate work.

The required velocity may be given to the patrice in any desired manner, but the most practical and efficient means known to me is that of a fall hammer dropping from a sufficiently high elevation. The velocity which must be given to the patrice at the moment of impact in order to secure my improved results, and which I refer to herein as a high degree of speed, is a velocity of from about 80 twenty-five feet per second up to seventy-five and one hundred, or even more, feet per second; and this velocity may be secured by a drop hammer having a clear fall of from about 85 ten feet upward.

In the process above referred to, upon which the present invention is an improvement, it was proposed to use the ordinary drop hammer employed in the arts having a fall of from two to six feet. The high degree of speed 90 necessary to the practice of my invention therefore cannot be secured by the use of the drop hammer as heretofore commonly employed in the arts; and I have found it necessary to obtain specially constructed drop 95 hammers of much more than the usual height. I have used with excellent results drop ham- 100

mers having a clear fall of twenty-six feet, and from that up to seventy-five feet.

In carrying out the complete process the die block—preferably of steel or iron faced with steel—is preferably first heated that it may more readily receive the patrice. The die block may be heated in any ordinary furnace, but it is desirable that the heating should be effected in such manner that the formation of scales upon the surface of the die block, due to the oxidation of the metal while hot, is avoided. Any suitable expedient for thus preventing oxidation of the surface of the die block, now known or hereafter devised, may be employed for the purpose. The most practicable and best means known to me consist in covering the face of the die block with a close-fitting cap, and inclosing the die block and cap in an air-tight, close-fitting casing of suitable material before placing it in the furnace. The die block thus protected and placed in the furnace is brought to such a degree of heat as desired. I find that the best degree of heat for this purpose is a white or welding heat, but other degrees of heat may be employed. The heated die block is then taken from the furnace, the inclosing hood is removed, and the die block is placed under the hammer; the close-fitting cap is then removed and the impact of the patrice is effected before exposure to the atmosphere can cause oxidation of the surface of the die block. Sometimes it is possible to dispense with the inner close-fitting cover where the reliefs are low and the surfaces plain, so that the effects of oxidation can be removed from the die block by the use of tools. I do not limit myself in carrying out the above mentioned operations to the use of a patrice made of any particular material or made in any particular manner. I prefer to make the patrice by casting in a suitable mold from a form or pattern, using any suitable metal. The best metal known to me for the purpose is iron, including under that term steel. I prefer to use cast iron, adding thereto while molten about six per cent. of steel chips.

The process which is the subject-matter of my present application may be practiced with very many forms of apparatus, and I do not confine the practice of the process to the use of any particular form or construction thereof. I will however describe the most suitable form of apparatus now known to me for the purpose.

In the drawings annexed to this specification and forming a part thereof, Figure 1 shows in section a die block and the swage or die holder in which the die block is held while receiving the impression, and in elevation the hammer carrying the patrice and the guides between which it works up and down, the position of the parts being that immediately following a blow of the hammer. Fig. 2 is a side view of the same partly in section on line 2—2, Fig. 3. Fig. 3 is a plan view of the die holder and die block partly in sec-

tion on line 3—3 of Fig. 2. Fig. 4 represents mechanism hereinafter described for catching the hammer on the rebound, the clutches being shown withdrawn from that position in which they engage with the ratchets. Figs. 5 and 6 are respectively longitudinal and cross vertical sections, on an enlarged scale, of a die block, its cap and casing.

The die block A is, as I have stated, preferably of steel or iron faced with steel, and is of rectangular or circular or other desired form. The top surface may be flat, but I prefer to have it made with a central projection or fullness, as shown, sloping from the center to points near the edges of the block. The object of this fullness is to secure a greater degree of adaptability in the metal of the die block to the shape of the patrice than would be possible if the surface of the die block were plain. The first impact of the patrice being upon the apex of the fullness of the die block, this part of the die block is free to adapt itself to the configuration of the patrice and to completely fill all its recesses before the movement of the patrice is arrested by the contact of its flat surface with the face of the die block. Moreover, this fullness in the die block permits the air to be driven from the center outward from between the patrice and the die block, preventing the inclosure of air between approaching surfaces, the effect of which would be, if it occurred, to keep the metal of the die from following into the sharp angles and recesses of the patrice and would more or less dull the impression, preventing the production of a sharply defined die. The block is provided with a cap a so shaped as to closely fit its surface and is, thus protected, inclosed in an air-tight case of appropriate material and shape. For this case I prefer to use some refractory material, such as plumbago, formed or pressed into shape. The form of case shown herein consists, (see Fig. 5) of a plate b on which the die rests, and a cover c inclosing the die block and resting upon the plate b in such manner as to exclude air.

The channel tool or die holder in which the die block is held while being impressed consists, in the preferred form which I have shown herein, of a solid block of steel d of suitable size, for instance three and a half feet long by twelve or thirteen inches wide and eight or nine inches high, in which is planed a channel g about four inches wide and half the depth of block, to receive the die block. Steel reinforcing straps e embracing the sides of the block are shrunk on and fastened by steel bolts f passing through the body of the block. Other large bolts, four of which are shown, pass through the lower part of the block at intervals of its length for the purpose of strengthening it against the tendency to split longitudinally under the stress of the blow of the hammer. At each end of the block and just above the level of the bottom of the channel are cut two slightly tapering

key-ways *h* adapted to receive the tapering keys *k* which are somewhat longer than the width of the block and which form end bearings for the die block, or for packing pieces between the die block and the keys and are driven in to wedge the die block in place. These packing pieces *i* are used for the purpose of adapting the die holder to dies of different lengths. Packing pieces may be also inserted lengthwise of the dies to permit the die holder to be used for die blocks of different widths. For certainty in centering the die block under the hammer, it is convenient to first drive one of the channel keys home, place the proper amount of packing between this channel piece and the die block to bring it into its proper position under the hammer, drop in the die block and wedge the die block in place by driving in the other key against a suitable amount of packing interposed between the key and die block. Great strength in the die holder and tight and secure wedging of the die block are desirable on account of the enormous spreading force exerted upon the die block by the blow of the hammer. It is in order to hold the metal of the die block up to the patrice, and thus insure a perfect impression, at the same time avoiding distortion of the die block, that the die block is so tightly and powerfully confined.

The block *d* stands upon a suitable foundation between two upright guides *m*, *n*, between which the hammer *o* slides up and down, suitable power apparatus being provided for raising the hammer, and a suitable trip operated from below for permitting it to fall. The weight of the hammer will vary with the character of the work to be done and the distance it is caused to fall. Within certain limits reduction in the weight of the hammer may be compensated by increased fall and vice versa. For ordinary light work, such as making dies for scissors, hammer heads, wrenches and other small tools, I prefer to use a hammer weighing about one thousand pounds dropping from a height of about fifteen feet. The hammer preferably carries a hardened steel hammer block *p*, adapted to enter the channel of the die holder, to the striking face of which is attached the patrice in any suitable manner. I find it most convenient to fasten the patrice detachably, so that its connection with the hammer may be broken by the shock of impact with the die block and the patrice left resting on or in the die block as the hammer recedes after the blow. This may be done by the use of a cement, such as plaster of paris which is the best cement known to me for the purpose, spreading the cement over the face of the hammer block in a plastic condition and applying the patrice thereto; but the patrice may be fastened to the hammer block in any other suitable manner. It is very desirable in carrying out this process to provide means for preventing the hammer from making a double blow upon the die

block. The impact of the hammer, when moving at high speed, upon the die block causes it to rebound and to fall back, striking the die block again with great force unless some means are provided for preventing the second descent of the hammer. The effect of such a second blow is frequently to destroy the die cut by the first blow since it will sometimes happen that two such successive blows will not be exactly coincident with each other. This is the case where the patrice is attached permanently to the hammer, and also where it is detachably affixed to it, as by cement. In the latter case the patrice is sometimes partially pulled out of the die block before it is detached from the hammer, so that, if struck by the hammer after the rebound, it would be liable to diverge from its original impression and spoil the die. The means which I preferably use for preventing the second blow of the hammer are shown in Figs. 1, 2 and 4 and consist of two ratchet bars *q* *q'*, one attached to each of the uprights *m*, *n*, and two clutches *B* pivoted upon bolts *s* *s'* fixed in the hammer and having on their lower ends teeth adapted to mesh with the ratchets. To the hammer face is fixed a vertical mandrel *t*, the ends of which are held by clips *u* *u'*. About the mandrel is a cylinder *E*, the head *E'* of which has in it a hole through which the mandrel passes. The lower end of the cylinder fits loosely about a collar *v*, free to slide up and down on the mandrel. About the mandrel is a spring *x* held under a slight pressure, between the head of the cylinder and the collar. Near the top of the cylinder and on opposite sides are two external lugs *y* *y'*. Each of the clutches *B* is provided with a pair of arms *B'* *B*². These arms *B'* are so adjusted that when their upper ends rest against the lugs *y*, *y'*, as shown in Fig. 4, the arms *B*² support the collar *v* and compress the spring *x*.

The operation of this device is as follows: The clutches normally rest with their arms *B'* against the lugs *y* as shown in Fig. 4, in which position the teeth on their lower ends cannot engage with the teeth on the ratchets *q* *q'*. When the hammer descends and strikes the die block the momentum of the cylinder *E* carries it downward against the pressure of the spring *x* until the lugs *y* *y'* release the arms *B'* and permit the clutches to spring outward under the pressure of the spring *x*, acting through the collar *v* and the lower arms *B*², until the parts assume the position shown in Fig. 1. The lugs *y* *y'* are now caught under the upper hooked ends of arms *B'*. The cylinder is thus held in its depressed position, and the clutches are forced outward and drag along the teeth of the ratchets as the hammer continues to rise on its rebound. As soon as the hammer ceases to ascend the teeth of the clutches engage with the teeth of the ratchets and prevent a second descent. When the hammer is to be again raised the lower ends of the clutches *B* are pressed together,

which does not require a great exertion of force, and the cylinder E immediately returns to its normal place and locks the clutches B in the position shown in Fig. 1. Handles D 5 are inserted in the lower ends of the clutches for use in pressing the clutches together. While this is the preferred form of apparatus for preventing a second blow upon the die block I do not confine myself to the use there- 10 of, but may employ any apparatus suitable for the purpose, or may use the hammer without such apparatus.

In practicing my invention with the described apparatus the cap a is first applied to 15 the die block, the die block is then inclosed in the case c resting on the base b, and the incased die block is then placed in the furnace and suitably heated. The die holder is then adjusted to receive the die block and 20 the patrice is attached to the hammer block; the heated die block is removed from the furnace, the casing taken off, and the die block dropped into the die space prepared for it in the die holder. The key is then driven home, 25 wedging the die block between the packing pieces. The cap a is removed and immediately the hammer is tripped and drops, and the patrice is driven into the die block. The hammer rebounds and is caught by the 30 clutches, and there suspended until it is again raised. Where the patrice is attached to the hammer block by cement the force of the blow destroys the cement and breaks the connection; and the hammer block rises leaving the 35 patrice in the die. This method of attaching the patrice to the hammer block is advan- tageous for a number of reasons; first, it is convenient and permits patrices of different sizes to be centered upon the face of the 40 hammer block. Again, it is desirable in many cases to leave the patrice in the die until the latter has cooled, so as to effectually prevent the access of air to the surface of the die while hot. This can be more effectually 45 done by leaving the patrice in the die than by filling the die with powdered charcoal which is a method of excluding the air sometimes resorted to. After the die is cold its surface may be brushed with a solution of muriatic 50 acid which removes any traces of scale which may have formed and leaves the surface perfectly smooth. The die is then ready to be hardened and used. I also would regard motion of the die block against a stationary pa-

trice as the equivalent of motion of a patrice 55 against a stationary die block.

An advantage of the process above set forth to which I wish to call particular attention is the fact above adverted to that the high velocity of the patrice at the moment of impact 60 makes it possible to penetrate the steel die block with a patrice formed of metals very much softer and more fragile, and therefore more easily worked, than a patrice cut from rolled cast steel which must be employed 65 where the patrice is placed upon the die block and driven into it by a hammer descending and striking the patrice. Thus as above suggested, a cast patrice may be employed or even a patrice stamped or struck by means of 70 a die from a comparatively soft metal. I am thus enabled to use a patrice much less difficult to make and much less costly, while at the same time I obtain better results than can be secured by any other process. 75

Certain features of the machine herein de- 80 scribed are claimed in my applications, Serial Nos. 333,357 and 435,478, filed December 11, 1889, and June 4, 1892, and are therefore not claimed herein.

Having thus described my invention, what I claim, and desire to protect by Letters Patent, is—

1. The process of making steel dies, which consists in preparing and heating a suitable 85 steel or iron and steel die block and causing the patrice to move at a high degree of speed as hereinbefore defined, and while so moving to strike the die block and cut the die at a single blow, substantially as described. 90

2. The process of making steel dies, which consists in preparing and heating a suitable steel or iron and steel die block and preparing a patrice from a metal which is compara- 95 tively soft or capable of being readily brought to the desired shape, as cast iron, and causing the patrice to move at a high degree of speed as hereinbefore defined, and while so moving to strike the die block and cut the die at a single blow, substantially as set forth. 100

In testimony whereof I have hereunto set my hand in the presence of two subscribing witnesses.

GEORGE F. CHAMPNEY.
